(57) **CLAIM**

The ornamental design for a connector for massager as shown and described.

DESCRIPTION

FIG. 1 is a perspective view of a connector for massager showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the connector for massager that form no part of the claimed design. The connector for massager is shown with a symbolic break in its length and the appearance of any portion of the connector for massager between the break lines form no part of the claimed design.
